UNITED STATES PATENT OFFICE.

BENJAMIN F. BERRY, OF ST. LOUIS, MISSOURI, ASSIGNOR TO H. M. POLLARD,
OF ST. LOUIS, MISSOURI.

ENVELOP-MACHINE.

SPECIFICATION forming part of Letters Patent No. 687,552, dated November 26, 1901.

Application filed May 20, 1901. Serial No. 61,000. (No model.)

To all whom it may concern:

Be it known that I, BENJAMIN F. BERRY, a citizen of the United States, residing in the city of St. Louis, in the State of Missouri, have 5 invented certain new and useful Improvements in Envelop-Machines, of which the following is a full, clear, and exact description, reference being had to the accompanying drawings, forming part of this specification.

10 My invention relates to that class of machines used in the manufacture of envelopes from prepared blanks.

The invention consists in features of novelty hereinafter fully described, and pointed 15 out in the claims.

Figure I is an end view of the machine. Fig. II is a rear elevation. Fig. III is an enlarged vertical sectional view taken on line III III, Fig. I. Fig. IV is an enlarged vertical sectional view taken on line IV IV, Fig. I. Fig. V is an enlarged vertical sectional view taken on line V V, Fig. II. Fig. VI is a detail view of one of the flap-folders looking at the inside face thereof. Fig. VII is an enlarged detail view of the upper end of one of the flap-folders. Figs. VIII, IX, and X are enlarged cross-sectional views taken on the lines VIII, 20 IX, and X, Fig. VI. Fig. XI is an enlarged detail view, partly in plan and partly in horizontal section, of portions of the initial feed-rollers and the gumming device. Fig. XII is an enlarged detail view, partly in plan and partly in horizontal section, taken on the line XII XII, Fig. V. Fig. XIII is an enlarged detail perspective view of one of the gumming-wheel scrapers. Fig. XIV is an enlarged detail view of fragments of one of the folders and the plate by which the folder is supported. Fig. XV is a view of the envelop-blank 25 previous to its being folded. Fig. XVI is a rear view of the envelop-blank partially folded. Fig. XVII is a rear view of the completed envelop.

1 designates the end walls of the machine-frame.

2 is the top of the frame, surmounted by a top plate 3, provided with a centrally-located slot 4. (See Figs. I and V.)

5 designates a drive-shaft journaled in the 30 end walls of the machine-frame and provided with a drive-pulley 6, that receives a belt

through which power may be applied to operate the mechanism of the machine.

8 is a spur-wheel fixed to the drive-shaft 5 exterior of the machine-frame, and on the shaft 5 between the frame end walls 1 is a delivery feed-roller 9, that is arranged to revolve with the drive-shaft 5. Positioned opposite the delivery feed-roller 9 is a delivery feed-roller 10, that is carried by a shaft 11, 60 provided with a spur-wheel 12, arranged in mesh with a spur-wheel 8, so that the roller 10 is driven in unison with the roller 9. The roller 10 is adjusted toward the roller 9 by adjustment-screws 13, seated in the frame 65 end walls and arranged to bear against the movable journal-boxes 14 in which the shaft 11 is mounted.

15 designates a series of carrier-rollers having journals 16 mounted in the frame end 70 walls and arranged in a tier one above another.

17 designates a series of sets of narrow pressure carrier-rollers, the series being equal in number to the carrier-rollers 15 and arranged in opposition thereto. The sets of pressure 75 carrier-rollers 17 are adjustably mounted on shafts 18 and held by set-screws 17^a. Each shaft 18 is journaled in movable boxes 19, seated in slots 20 in removable frames 21, set into recesses in the frame end walls 1 and 80 secured thereto by screws 22 or other suitable means. (See Figs. I and V.) The pressure carrier-rollers 17 are yieldingly held to the carrier-rollers 15 by springs 23, that are backed by adjustment-screws 24, through the 85 medium of which the tension of the springs may be increased or diminished.

The journals 16 of the rollers 15 are each provided with spur-wheels 25, fixed thereto exterior of the frame of the machine, and fixed 90 to the shafts 18 of the rollers 17 are spur-wheels 26, that mesh with the spur-wheels 25. Power to drive the spur-wheels 25 and 26 is transmitted from the spur-wheel 8 on the drive-shaft 5 through a series of transmitting- 95 pinions 27, that mesh with the spur-wheel 8 and the spur-wheels 25. The sets of pressure carrier-rollers 17 are always used of a combined width less than the length of the envelop to be made in order that the adjustable 100 flap-folders, hereinafter described, may be positioned as closely together as is requisite to

suit the requirements of the envelops being manufactured in the machine. By mounting the pressure-rollers in the removable frames 21, said frames may be readily lifted from the 5 end walls 1 of the machine-frame and the pressure carrier-rollers removed therewith, so that the various parts may be readily gotten at for repairs, &c.

28 designates an initial feed-roller having 10 journals 29 mounted in the frame end walls 1 and positioned above the uppermost carrier-roller 15.

30 designates a shaft positioned in horizontal line with the axis of the roller 28 and 15 mounted in movable journal-boxes 31. (See Fig. XI.) The journal-boxes 31 are held in any desired set position by adjustment-screws 32. On the shaft 30 are movable rings 33, that are adjustably held to the shaft by set- 20 screws 34, (see Fig. XI,) so that said rings may be shifted on said shaft according to the length of the envelop being made and passed between the initial feed-roller 28 and the rings 33. On the shaft 30 are gumming-wheels 35, 25 adjustably held by set-screws 36, so as to be capable of movement longitudinally of said shaft according to the length of the envelop being made and through the medium of which the end flaps of the envelops are gummed in 30 a manner hereinafter described. The gumming-wheels 35 are positioned immediately above and rotate in gum-reservoirs 37, mounted on cross-bars 38, secured to the machine-frame and provided with longitudinally-extending slots 39, that receive adjustment-bolts 40, by which the reservoirs are held in any desired fixed position, as seen in Figs. II, 35 V, and XI.

41 designates a cross-bar secured to the machine-frame (see Fig. V) and provided with longitudinally-extending slots 42.

43 designates arms adjustably secured to the cross-bars 41 by adjustment-bolts 44, that pass therethrough and through the slots 42 45 in the cross-bar 41. The arms 43 extend in the direction of the gumming-wheels 35, and mounted thereon are bifurcated scrapers composed of members 45, that straddle the gumming-wheels. The scraper members 45 are 50 connected by an adjustment-screw 46, by which they may be drawn more closely together or separated more or less to embrace the gumming-wheels as closely as desired to remove the surplus gum therefrom as the gumming-wheels rotate.

47 designates bifurcated fingers adjustably secured to cross-bars 48, provided with longitudinally-extending slots 49, that receive adjustment-bolts 50, seated in said fingers, so 60 that they may be moved longitudinally of the initial feed-roller 28. The bifurcated inner ends of the fingers 47, extending downwardly between the initial feed-roller 28 and the ring-carrying shaft 30 and the arms 47^a thereof, 65 straddle the gumming-wheels 35, as seen in Figs. V and XI. The finger-arms 47^a serve to hold the envelop-flaps passing between

the feed-roller 28 and the gumming-wheels projected toward said gumming-wheels, in order that the gum may be effectually applied thereto.

51 and 52 are receiving-rollers, mounted immediately beneath the top plate 3, that receive the envelop-blank as it is introduced through the slot 4 in the top plate 3 and delivered thereto. The receiving-roller 52 is mounted in movable journal-boxes backed by springs 53, so that said roller 52 is yieldingly held to the roller 51. The initial feed-roller 28 is driven by power communicated to a spur-wheel 54 from a transmitting-pinion 27, that meshes with the uppermost spur-wheel 25, and the spur-wheel 54 meshes with a spur-wheel 55 to drive the shaft 30. A transmitting-pinion 27, in mesh with the spur-wheel 54, conveys power to the spur-wheel 56 on the receiving-roller 52, and the spur-wheel 56 in turn meshes with a spur-wheel 57 on the shaft of the receiving-roller 51 to drive said last-named roller.

The envelop-blanks A of the form shown in Fig. XV are fed onto the top plate 3 of the machine and are carried through the slot 4 therein by a folder-blade 58, that folds them on the line between the back and front of the envelop and carries them downwardly to a position to be caught by the receiving-rollers 51 and 52, by which they are caught and delivered to the initial feed-roller 28 and the rings 33 on the shaft 30. The folder-blades 58 are carried by an arm 59, that has a vertical guide 60, arranged to operate vertically in the groove 61, contained by one of the frame end walls 1, (see Fig. III,) whereby the folder-blade is arranged to move vertically to cause it to move into and out of the slot 4 in the top plate 3. Attached to the vertical portion of the folder-blade arm is a reciprocating arm 62, that is provided with a slot 63.

64 designates a stub-shaft fixed to the machine-frame, and projecting outwardly therefrom and journaled in said stub-shaft is a cam 65, that carries a gear-wheel 66. The stub-shaft 64 passes through the slot 63 in the reciprocating arm 62, carried by the folder-blade arm, so that said arm is rendered capable of reciprocal movement on said stub-shaft, and rotatively mounted on the reciprocating arm is a roller 67, that travels on the periphery of the cam 65, being held thereto by a spring 68, that is connected to a stem 69, projecting from the stub-shaft 64, and a stem 70, projecting from the reciprocating arm 62. By this arrangement the roller 67 is maintained in constant bearing against the periphery of the cam 65, and as said cam is rotated the reciprocating arm 62 is raised and lowered to effect the vertical movement of the folder-blade-carrying arm 59 and the folder-blade 58 to feed the envelop-blanks into the machine in the manner stated. The gear-wheel 66 is driven by a pinion 71, that is arranged in mesh therewith and also in mesh with the spur-wheel 57 on the shaft of

the receiving-roller 51. In order to provide for variation in the speed of movement of the folder-blade and the arm by which it is carried, gear-wheels 66 of varying sizes may be used. With this object in view the pinion 71 is mounted on a stub-shaft 72, that is movably seated in a slot 73, contained by a hanger-bracket 74, (see Figs. I and IV,) attached to the machine-frame, so that said pinion 71 may be raised and lowered in said hanger-bracket to move it into mesh with the gear-wheel 66 after a change of gear-wheels is made. The stub-shaft is steadied by a link 75, mounted on the shaft of the receiving-roller 51.

76 designates a plate fixed to the frame of the machine and cut away at intervals to permit of the carrier-rollers 15 operating therethrough, as seen in Fig. V. The plate

76 is provided intermediate of the carrier-rollers 15 with slots 77. (See Fig. II.) The slots 77 receive bolts 78, provided with adjustment-nuts 79. The slotted plate 76 is arranged to support the end-flap folders, to be presently described, said folders being movably connected thereto by the bolts 78 and adjustment-nuts 79 thereon, so that they may be moved inwardly or outwardly to properly position them according to the size of the envelope being produced in the operation of the machine.

The end-flap folders (two in number) are each composed of a single member 80, and they are positioned between the carrier-rollers 15 and the shafts 18 of the pressure carrier-rollers 17 beyond the ends of said rollers 17, as most clearly seen in Fig. XII. Each folder is provided with a longitudinal groove 81, extending from end to end thereof and having an enlarged mouth 82 at the upper end. Extending from one side of each folder from a point below the upper end thereof is a groove 83, that leads downwardly and merges into the groove 81 at a point above the lower end of the folder.

84 is a tongue integral with the folder member at the upper end thereof and projecting downwardly between the grooves 81 and 83, so as to separate them from each other, as seen in Figs. VI, VIII, and IX, the said tongue being of greatest diameter at its upper end and connection to the folder member and gradually decreasing in diameter to its lower end, where it terminates in a point. (See Fig. VI.) Beneath the lower end of the tongue 84 the groove 81 is unobstructed, and said groove is gradually contracted toward its lower terminus.

85 designates a pair of curved pressure-strips having their ends fixed to cross-bars 86, attached to the movable frame 21, by which the pressure-rollers 17 are carried. These pressure-strips are designed for service in holding the portions of the envelopes that project beyond the ends of the pressure-rollers 17 against the carrier-rollers 15, so as to avoid liability of the envelopes buckling between the ends of said pressure-rollers and the flap-folders as they are carried through said fold-

ers by the rollers 15 and 17. As the envelopes leave the flap-folders they are caught by the delivery feed-rollers 9 and 10 and carried therethrough onto endless tapes 87, that are arranged to travel on the delivery feed-roller 9 and also on a discharging-roller 88, that is opposed by a discharging-roller 89, the shaft of which is adjustably held by adjustment-screws 90. After passing between the discharge-rollers 88 and 89 the envelopes are conveyed from the machine on endless belts 91 to any desirable point of delivery, said last-named belts being driven by the roller 88, about which they pass. The rollers 88 and 89 receive power-driving connection from the spur-wheel 12, that is conveyed from said spur-wheel to spur-wheels 92 through a transmitting gear-wheel 93, that meshes with one of said spur-wheels 92.

The operation of this machine is as follows: The prepared envelop-blanks being properly positioned on the top plate 3 and the mechanism of the machine being in motion, the folder-blade 58 descends upon each envelop-blank as it is placed on the top plate and carries the blank in a folded condition downwardly, so that it is caught by the receiving-rollers 51 and 52, which deliver the folded blank to the initial feed-roller 28 and the opposing feed-rings 33 on the shaft 30. As the folded blank passes between the feed-roller 28 and rings 33 the end flaps receive the contact of the gumming-wheels 35, thereby gumming said flaps, so that they are ready to be pressed to the back C of the envelop. The blanks then descend to and between the upper set of carrier and pressure rollers 15 and 17, by which they are caught in their folded condition, being carried downwardly between the succeeding series of rollers 15 and 17. As the upper set of rollers 15 and 17 carry the envelop-blanks downwardly the ends thereof first pass into the mouths 82 of the longitudinal grooves 81 in the folder members 80, the ends of the envelopes at this time being extended in a straight line, as seen in Fig. VII. The wall of the grooves 81 and 83 being tapered, as seen in Figs. VIII and IX, as the envelop-blanks are carried downwardly by the rollers 15 and 17 the end flaps B of the envelop-blanks are gradually curled toward the tongues 84 in the folder members, while said tongue holds the envelopes in flat condition, preventing buckling thereof while the envelopes are passing through the folders, as illustrated in the successive positions seen in Figs. VIII and IX, and the taper of the wall of the groove 81, into which the groove 83 merges at the lower end of the tongue, being in like proportion to the taper of said wall opposite the tongue the end flaps B of the blanks are carried onto the backs C of the envelopes, as seen in Fig. X. As the blanks are conveyed through the lower end of the groove 81 to the terminus thereof the flaps are pressed tightly to the backs of the envelopes, so that while they are passing through the contracted lower end of

the groove 81 the gummed flaps are effectually pasted to the envelop-backs. The envelops are then in a completed condition and pass between the delivery feed-rollers 9 and 10 5 onto the endless tapes 87, thence between the delivery-rollers 88 and 89, and onto the conveyer-belts 91.

I claim as my invention—

1. In an envelop-machine, the combination 10 of a pair of folders, a series of carrier-rollers, and a series of sets of adjustable pressure carrier-rollers positioned on shafts opposite said carrier-rollers, substantially as described.
2. In an envelop-machine, the combination 15 of envelop-carrier rollers, a pair of folders through which the ends of the envelops are conveyed, and pressure - strips extending transversely of said carrier-rollers and adapted to bear against the envelops as they are 20 conveyed between said carrier - rollers and through said folders, substantially as described.
3. In an envelop-machine, the combination carrying and folding means, means for feeding 25 the envelops to said carrying and folding means, a pair of gumming-wheels and bifurcated fingers arranged to straddle said

gumming-wheels and press the envelop-flaps thereagainst, substantially as described.

4. In an envelop-machine, the combination 30 of gumming means, a series of carrier-rollers, a pair of folders through which the ends of the envelops are conveyed, a removable frame mounted in the main frame of the machine, a series of pressure carrier-rollers mounted 35 in journal-boxes movably supported in said removable frame, and means whereby said pressure carrier-rollers are yieldingly held toward said carrier-rollers, substantially as described. 40

5. In an envelop-machine, the combination of gumming means, a series of carrier-rollers between which the envelops are passed; a pair of folders through which the ends of the envelops are conveyed, and pressure-strips 45 arranged to bear against the envelops as they are conveyed between said carrier-rollers and through said folders, substantially as described.

BENJAMIN F. BERRY.
